[57] **CLAIM**

The ornamental design for a chair frame, as shown and described.

DESCRIPTION

FIG. 1 is a perspective elevational view, the view being taken from the rear and side, and the fabric for the chair frame being shown in diagrammatic lines only;

FIG. 2 is a side elevational view, the view from each side being identical;

FIG. 3 is a top plan view;

FIG. 4 is an under plan view, taken on the line 4—4 of FIG. 2;

FIG. 5 is a front elevational view;

FIG. 6 is a rear elevational view;

FIG. 7 is a perspective elevational view of a modified embodiment;

FIG. 8 is a side elevational view, the view from each side being identical thereof;

FIG. 9 is a top plan view thereof;

FIG. 10 is an under plan view, taken on the line 10—10 of FIG. 8 thereof;

FIG. 11 is a front elevational view thereof; and

FIG. 12 is a rear elevational view thereof.

This application is a continuation-in-part of U.S. application Ser. No. 248,723, filed Mar. 30, 1981, entitled chair frame.
